UNITED STATES PATENT OFFICE

2,637,505

WEB TENSIONING MEANS

Kenneth G. Laycock, Shavertown, Pa.

Application January 28, 1950, Serial No. 141,127

16 Claims. (Cl. 242—75)

1

The present invention relates to new and useful improvements in web tensioning devices for automatically controlling the tension of a paper web as it is fed from a web roll to a rotary printing press.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a side elevation with certain parts broken away showing a typical and preferred embodiment of the present invention;

Figure 2 is a detailed sectional view taken on the line 2—2 of Figure 1;

Figure 3 is a transfer sectional view taken on the line 3—3 of Figure 1;

Figure 4 is a fragmentary side elevation of the embodiment shown in Figure 1 but looking from the other side thereof; and

Figure 5 is a detailed side elevation of a modification of certain parts.

The present invention has for its object the provision of a novel and improved web roll tensioning device adapted to maintain a uniform tension on the web of paper as it is drawn from the web roll by the rotary printing press to which it is being fed. A further object of the invention is the provision of an improved web tensioning device which maintains the tension substantially constant regardless of the diameter of the web roll and the speed at which the web is drawn from the roll and which is not subject to variation due to irregularities in the shape of the web roll, and which may be pre-set to give the desired tension for different widths of web rolls and for different operating conditions of the printing press. Among the many advantages of the web tensioning device of the present invention are the improvement in first impression printing which results from its use and the better understanding of the functions of web tensioning in general that it teaches through its simple, easily understood adjustments and its very efficient action.

In accordance with the present invention,

means are provided for applying friction to a web roll supported for rotation, and these tensioning means are controlled by a pilot roller which is moved in accordance with changes in the web tension and is so connected as to increase or decrease the friction applied to the web roll. The pilot roller is supported in pivotally moveable arms, and when moved by an increase in the web tension causes a decrease in the friction applied to the web roll. The movement of the pilot roller, and the transmission of this movement to the brake or other means for applying friction to the web roll is also controlled by a relatively heavy mass which is resiliently connected to the pilot roller through spring linkage having variable resiliency so that the strength of the spring can be varied and maintained at the desired value thereby regulating the effect of the mass on the pilot roller. Means are also provided for restraining the free movement of the suspended mass and for this purpose friction braking or snubbing means are provided which exert more restraint on the mass in one direction of movement than in the other.

20 The connection between the spring supported mass and the pilot roller is illustratively provided by an arcuate saddle fixed to the pilot roller supporting arms and coaxial with the pivot for the arms but also moveable radially with respect to the pivot so that the lever arm ratio between the supporting arms and the surface of the arcuate saddle may be varied as desired.

It will be understood that the foregoing general description and the following detailed description as well are exemplary and explanatory of the invention but are not restrictive thereof.

Referring now in detail to the illustrative embodiment of the invention, the web roll 10 is supported by means of its shaft 11 and journals 12 formed in brackets 13 which extend laterally from the upright frame members 14, similar supports being provided at either end of the web roll 10. Tension is created in the web 16 drawn from the web roll 10 by means of a brake which comprises 25 brake drum 18 and brake shoes 19, the brake shoes being pressed toward each other and into contact with the drum 18 by means of the lever arms 20 which are pivotally supported by a link 22 mounted on the frame member 14 by means of the side lay adjusting wheel 24. The other ends of the brake levers 20 are interconnected by means of the turnbuckle link 26, the upper end of which is connected to a bell crank 28 having a long upwardly extending arm 29 and a short lever arm 30, the short lever arm detachably connecting the

upper end of the link 26 with the adjacent end of the upper brake lever arm 28. The length of the link 26 may be varied to compensate for wear of the brake shoes 19 by turning the screw threaded member 31.

As the web is drawn from the web roll 10 to the printing press it passes over guide rollers 34 and 35, and between them is looped over pilot roller 37 which is freely rotatable in supporting arms 38 which are pivoted in the upright frames 14 by means of shaft 39, and are preferably counterbalanced by means of the variably positioned weight 40. Also mounted on shaft 39 in fixed angular relation to the arms 38 is a depending arm 41 (see Fig. 3) which is operatively connected to the brake operating arm 29 by means of link 43. An increase in the tension of the web fed to the press causes the pilot roller 37 to move downwardly thereby moving bell crank 28 in a counter-clockwise direction to relieve the pressure on the brake shoes 19 so as to permit web roll 10 to rotate more freely and thereby effect a reduction in the tension of the web. Simultaneously a decrease in the tension of the web causes a reverse movement of these parts so that the brake pressure exerted by shoes 19 is increased to increase the web tension.

The tension of the web 16 also tends to move the pilot roller against the forces exerted by a relatively heavy mass 50 which is connected with the pilot roller by means of rod 52, spring linkage 54, rod 56, flexible cable 58 and an arcuate saddle 60 coaxial with and fixed to shaft 39 on which the pilot roller supporting arms 38 are mounted. By these means mass 50 moves up and down in accordance with movements of the pilot roller 37, and in the same way controls the position of the pilot roller 37 and the force applied by the braking shoes 19.

Mass 50 comprises a cylinder of heavy metal supported on a collar 62 at the lower end of rod 52, and the value of this mass may be varied by adding or removing the supplementary slotted members 50a.

The spring linkage of variable resiliency forms an intermediate connection between the rods 52 and 56, and the weight of the entire mass 50 is supported by this spring linkage and the connection between the mass 50 and the pilot roller 37 is through this spring linkage. The spring linkage 54 comprises a pair of lever arms interconnected by a shiftable pivot at one end and by a spring at the other end, one of the lever arms being connected at an intermediate point to the rod 52 while the other lever arm is connected at an intermediate point to the rod 56. As embodied this linkage comprises a bottom pair of short straps 64 forming a lever and an upper pair of short straps 66 forming another lever, which levers are normally substantially parallel to each other. At one end the straps 64 and 66 are interconnected by means of a link which comprises rod 68 fastened to a pivot block 70 pivoted between the straps 64 and extending upwardly and slidably through a pivot block 72 pivoted between the ends of straps 66. A compression spring 74 is mounted on the rod 68 and is compressed between the slideable pivot block 72 and the jam nuts 76.

At the other end the lever arms 64 and 66 are interconnected by means of a horizontally slideable link 78, having upper and lower pins 79 which cooperate with the slots 80 to provide the variably positionable pivotal connection between the lever arms. For positively moving the link 78 and holding it in the desired position, a bracket 82 is fixed to and extends upwardly from the lever arm

64 and carries hand wheel 84 having a threaded portion which extends through a threaded aperture in the link 78. Rotation of the hand wheel 84 moves the link 78 toward and from rod 68 serving as the link at the other end of the lever arms. Between the links 68 and 78, the lever arm is pivotally connected to the rod 56 and shifting of the link 78 varies the effective resiliency of the compression spring 74. Lever arm 64 is preferably rigidly connected to rod 52.

The arcuate saddle 60 provides a variable ratio between the movement of the pilot roller 37 and the movement of the mass 50 and is useful in adjusting the web tensioning mechanism for different widths of web as well as for any other reason. As embodied the arcuate saddle structure comprises an arcuate surface 90 to the lower end of which is fixed the end of flexible cable 58, the cable extending upwardly from the surface 90 so that it is substantially tangential to the surface. Surface 90 is carried by slide block 92 which is slidably mounted in guides 94 of the box frame 96 which is fixed on the pilot roller supporting arm pivot shaft 39 so as to have a fixed angular relation to the arms 38. A crank 97 connected to screw 98 cooperates with the slide block 92 so that the arcuate surface 90, which is normally coaxial with shaft 39, may be moved radially with respect to the shaft 39 thereby changing the lever arm ratio between the pilot roller 37 and the arcuate surface 90.

Flexible cable 58 passes over an idler pulley 100 and is connected to the upper end of mass supporting rod 56. Rod 56 is slidably guided by means of a bracket 102 extending from side frame 14 and which also serves as the abutment for compression springs 104 and 106 wound on rod 56. Collars 108 fixed on the rod 56 serve to limit free movement of the rod 56, and cooperate with springs 104 and 106 to prevent and resiliently check excessive movement of the rod 56 and the supported mass 50.

Means are also provided for frictionally restraining free movement of the mass 50 so as to avoid any tendency of the mass to vibrate, and preventing bouncing by the mass 50 such as might otherwise occur when a web roll is being run which has a flap, is eccentric, or otherwise deformed. For this purpose rod 52 is provided with an upwardly tapering wedge member 110 fixed thereto, the converging faces of the wedge being frictionally engaged by friction shoes 112. Friction shoes 112 are formed as inner faces mounted on blocks 114 and each of the blocks 114 is guided for horizontal movement toward the other in a box 116 depending from bracket 118 mounted on the side frame 14. Blocks 114 and their friction faces 112 are resiliently urged toward each other by means of the levers 120 and compression springs 122 also mounted on the bracket 118. The force of springs 122 is varied by means of the screw threaded member 124 at one end of each lever, the other end of the lever bearing against the outer face of the block 114.

In the operation of the preferred embodiment of the invention, a new web roll 10 is mounted on its journals 12 and is threaded over the guide rolls 34, 35 and the pilot roller 37 and is threaded through the press for printing. The brake mechanism is then reassembled and hand wheel 31 is adjusted to bring the brake shoes 19 to their normal position to compensate for any wear. Saddle 90 is then brought to its proper setting corresponding to the width of the web to be run and shiftable link 78 is moved to compensate for any weakening of the spring 74 which may have

occurred or to provide a different resiliency in the spring linkage 54. The mechanism is then ready for operation and gradual movements of the pilot roller 37 in a downward direction cause a gradual lessening of the friction applied by the brake to the web roll. However, any sudden movement of the pilot roller allows additional web to be payed out of the loop and while the brake shoes 19 are momentarily applied with decreased force to the web roll, if the movement of the pilot roller 37 is purely a momentary movement, it will regain its normal position without effecting any substantial movement of the mass 50 due to the resiliency of the spring linkage 54 and the friction means 110, 112. However, a continued increased in the web tension will cause an upward movement of the mass 50 and a corresponding increase in the pressure applied to the brake shoes 19 and the tension created thereby. When the mechanism is at rest, or when the web is running at a constant and unvarying tension, the weight of the mass 50 acts upon the pilot roller 37 to maintain the pilot roller at a fixed position as it is balanced against the pull exerted by the web. Any change in web tension causes a slow or rapid movement of the pilot roller 37 which is transmitted to the mass 50, but due to the inertia of the mass 50 rapid movements of the pilot roller are largely absorbed by the resiliency of the spring 74 while the mass 50 remains more or less stationary. Thus the mass 50 is used not only for its weight but also as an inertia member.

If it is desired to increase the tension to be normally applied to the web, the crank 96 may be rotated to move the arcuate surface 90 away from its pivotal center 39 thereby lengthening the leverage ratio between the pilot roller 37 and the brake connecting linkage as one entity and the mass 50 and its linkage as another entity thereby increasing the value of the mass 50 in relation to its applied force.

The friction members 110, 112 acting to restrain free movement of the mass 50, act with greater effect with one direction of movement than with the other; a decrease in web tension is corrected more rapidly than is an increase in web tension. This is not only of importance in providing for rapid braking of the web roll in case of a web break, but is also of importance in the normal running of the mechanism so as to prevent the web becoming slack at any time in its passage from the roll through the press.

Figure 5 illustrates a modified form of spring supported linkage interconnecting the pilot roller and mass whereby a wider variation of resiliency is obtainable than with the form shown in Figure 1. In Figure 5 rod 52 is rigidly and detachably connected to one end of strap 64 by pin A² and collar 120 so that strap 64 is supported by collar 120 against pivotal motion relative to the rod 52. Strap 66 is pivotally connected by pivot A¹ to rod 56, and the straps 64 and 66 are interconnected by means of the rod 68, spring 74 and pivot blocks 70 and 72 which are pivotally connected by pivot pins B² and B¹ to straps 64 and 66 between their ends. Slidably link 78 connected the other ends of straps 64 and 66 as in Figure 1. In the position shown in Figure 5 the spring 74 has a soft action and it can be given the effect of a much stiffer spring by connecting the rods 52 and 56 at pivot points B² and B¹ and by connecting the pivot blocks 70 and 72 at the pivot points A² and A¹.

The present invention in certain respects is an improvement upon the web tensioning apparatus

shown and described in my copending application Serial No. 8,179 filed February 13, 1948, but in other respects it is not so limited and is of more general application.

The invention in its broader aspects is not limited to the specific mechanisms shown and described but departures may be made therefrom within the scope of the accompanying claims without departing from the principles of the invention and without sacrificing its chief advantages.

What is claimed is:

1. In a web tensioning device for controlling the tension of a paper web fed from a web roll to a rotary printing press, having a web roll support, means for applying friction to the web roll to tension the web, a pilot roller moved by changes in the web tension and connected to increase or decrease the friction applied to the web roll, an increase in web tension causing a decrease in the friction, the combination of a mass, and a linkage having variable lever arm ratio connected between the pilot roller and mass, a spring forming part of the linkage, said linkage and spring being connected between said mass and pilot roller for supporting said mass with a variable resiliency.
2. A web tension device as claimed in claim 1 in which the pilot roller is supported in pivotally mounted arms, and an arcuate saddle coaxial with said arms to which said mass is connected by means of a flexible member tangential to the saddle.
3. A web tension device as claimed in claim 2 in which means are provided for radially moving the arcuate saddle.
4. A web tension device as claimed in claim 3 in which friction means are provided acting on the mass and principally restraining an upward movement of the mass.
5. In a web tensioning device for controlling the tension of a paper web fed from a web roll to a rotary printing press having a web roll support, means for applying friction to the web roll to tension the web, and a pilot roller moved by changes in web tension and connected to increase or decrease the friction applied to the web roll, an increase in web tension causing a decrease in the friction, the combination of a mass spring supported linkage of variable resiliency supported by the pilot roller and through which the mass moves and is moved by the pilot roller.
6. A web tension device as claimed in claim 5 in which said spring supported linkage comprises a pair of levers, a spring connected to one end of each lever, and a shiftable pivot means interconnecting the levers at their other end.
7. A web tension device as claimed in claim 6 having arms pivotally supporting the pilot roller, an arcuate saddle fixed to and coaxial with said arms and a flexible band connected to the mass and tangentially connected to said saddle.
8. A web tension device as claimed in claim 7 in which screw means are provided for radially moving the arcuate saddle to vary its position relative to the pilot roller supporting arms pivot.
9. In a web tensioning device for controlling the tension of a paper web fed from a web roll to a rotary printing press having a web roll support, means for applying friction to the web roll to tension the web, a pilot roller moved by change in web tension and connected to increase or decrease the friction applied to the web roll, an increase in web tension causing a decrease in the friction, the combination of a mass, and spring

supported linkage connecting the mass to the pilot roller to support the pilot roller and to move the pilot roller by the mass, said linkage including variable lever arms for changing the resiliency of the spring linkage.

10. A web tension device as claimed in claim 9 in which said spring supported linkage comprises a pair of levers, a spring connected to one end of each lever, and a shiftable pivot means interconnecting the levers at their other end.

11. A web tension device as claimed in claim 10 having arms pivotally supporting the pilot roller, and an arcuate saddle fixed to and coaxial with said arms.

12. In a web tension device for controlling the tension of a paper web fed from a web roll to a rotary printing press, the combination of friction means restraining the rotation of the web roll, a pilot roller moved by changes in the web tension and connected to increase or decrease the friction applied to the web roll, an increase in web tension causing a decrease in the friction, a mass for moving the pilot roller against the pull of the web, a pair of pivotally interconnected levers, a member flexibly connecting the pilot roller to one lever, another member interconnecting the mass to the other lever, spring means interconnecting the levers and acted on by the weight of the mass as the mass tends to move the pilot roller and is supported thereby, and means for relatively varying the distances of the spring from the pivotal interconnection and the pivotal interconnection from the flexibly connected members whereby the effective strength of the spring is varied.

13. A web tension device according to claim 12 in which pivoted arms rotatably support the pilot roll, the member flexibly connecting the lever to the pilot roller being adjustable toward and away from the pivot of said arms.

14. In a web tension device for controlling the tension of a paper web fed from a web roll to a rotary printing press, the combination of friction means restraining the rotation of the web roll, a pilot roller moved by changes in the web tension and connected to increase or decrease the friction applied to the web roll, an increase in web tension causing a decrease in the friction, a mass connected to move the pilot roller against the pull of the web, the connection including linkage comprising a pair of levers each having three pivot points, means pivotally interconnecting the levers at one of their pivot points, a spring interconnecting the levers at another of their pivot points, and the mass and pilot roller being connected to the third pivot point of the levers whereby the weight of the mass is resiliently supported by the spring, and means for relatively shifting the several pivot points of each lever with respect to each other whereby the effective strength of the spring may be varied.

15. A web tension device according to claim 14 in which the pivot points on each of the two levers are similarly spaced, the spring is connected between the central pivot points and the pivotal interconnection between the levers may be shifted towards and from the other pivot points.

16. A web tension device according to claim 15 in which the pilot roller is connected by linkage to energize the friction means, and the friction means comprises a brake acting on the web roll shaft.
